HOUSING FOR A VEHICLE LAMP

Charles J. Newman, Madison, Ind., assignor to The Grote Manufacturing Company, Madison, Ind., a corporation of Kentucky

Filed Dec. 6, 1968, Ser. No. 14,824

Term of patent 14 years

Int. Cl. D12—99

U.S. Cl. D48—32

FIG. 1 is a view in perspective of a housing for a vehicle lamp embodying the invention.

FIG. 2 is an elevational view thereof.

FIG. 3 is a plan view thereof.

FIG. 4 is an end elevational view thereof.

FIG. 5 is a sectional view taken from line 5—5 in FIG. 2.

FIG. 6 is a diagrammatic view in section on the line 6—6 of FIG. 2.

The back face of the illustrated embodiment is substantially planiform as best illustrated in the cross sectional views, FIG. 5 and FIG. 6.

I claim:

The ornamental design for a housing for a vehicle lamp, as shown and described.
